United States Patent Office

Des. 218,920
Patented Oct. 6, 1970

218,920

OVEN

Joseph B. Diamond, Broomall, Pa., assignor to Dolly Madison Industries, Inc., Philadelphia, Pa., a corporation of Delaware

Filed Sept. 16, 1969, Ser. No. 19,163

Term of patent 7 years

Int. Cl. D7—04

U.S. Cl. D81—4

FIG. 2.

FIG. 1.

FIG. 4.

FIG. 3.

FIG. 6.

FIG. 5.

FIG. 1 is a perspective view of an oven embodying my new design, and showing the front and righthand side thereof;

FIG. 2 is a top plan view of the oven;

FIG. 3 is a lefthand side elevation of the oven;

FIG. 4 is a front elevation of the oven;

FIG. 5 is a bottom plan view of the oven; and

FIG. 6 is a rear elevation of the oven.

I claim:

The ornamental design for an oven, as shown.
